FIG.1

FIG.2

ROCKET WITH THERMAL CONTROL FOR INFLUENCING THE WEATHER

The invention refers to a rocket for influencing the weather which has an explosive charge and the substance to be atomized in its head portion.

With the present methods for the prevention of hail and for influencing the weather several substances forming nucleus are brought by means of rockets into thunder-clouds or hail-clouds consisting of under-cooled water particles or tiny ice nucleus. In most cases the rockets have explosive charges being ignited in accordance to a time delay. At this ignition the seed substances being provided in solved or liquid form are atomized. It has shown that just a very small portion of these substances are present in the desired crystalline form corresponding to the ice crystals; the major portion however is puffed off ineffectively.

According to the newest scientific knowledge the zone in hail-clouds being effective for the utilisation of seed substances is assumed in the temperature range between -30° and -40°C . The ignition at these isothermes, i.e., the discovering of their different levels, can be determined approximately only even when using the sounding by radar and a corresponding time ignition.

It is an object of the invention to effect this ignition exactly in the effective zone. In accordance with the invention it is proposed to provide a thermocouple one soldered junction of which is provided at the exterior of the rocket and the other soldered junction is kept on a constant temperature. Additionally a switch which can be adjusted to the desired thermoelectric voltage, and an electrical ignition for this explosive charge are connected to the thermocouple which ignition is actuated by this switch.

The invention makes it possible to switch on the electrical ignition after an exterior temperature in the atmosphere is given at which temperature the optimal efficiency of the seed substance is to be expected.

The invention will now be explained by way of the drawings:

FIG.1 shows the head of a rocket and

FIG. 2 the diagramm for the electrical ignition.

The thermocouple 1 has a measuring point 2 arranged at the exterior surface 3 of the rocket. The second measuring point 4 is maintained at a determined temperature by a heat insulation 5. Since the time of flight of the rocket is short the temperature of the measuring point 4 can be the temperature at the launching platform. The reference numeral 6 shows the ignition circuit. Batteries 7 provide the voltage necessary for the ignition itself a heated filament 8 and an ignition pellet 9 are provided. The ignition pel-

let can, as this is usual, consist of a mixture of aluminum powder, barium peroxide and shellac. The ignition pellet 9 and the heated filament 8 are surrounded by a thermite block 10. The space 11 is filled by the substance to be atomized. The head of the rocket is protected by a heat insulation 12 against the space 13 for the rocket composition.

According to FIG. 2 the measuring points 2 and 4 of the thermocouple 1 are connected to an amplifier 14. The measuring point 4 is surrounded by an insulation 5. The batteries 7 are also connected to the amplifier, however the connection is given by a switch 15. The amplifier 14 actuates a trigger 16 which operates an electronic switch 17 supplying the heated filament 8 with current. If the desired ignition temperature is measured by the thermocouple 1 the trigger 16 is actuated and the switch 17 is closed, now the filament begins to glow and thus the rocket is ignited. On account of the rapid heating by means of thermite or like charges a complete evaporation of the nucleous forming substance is effected and it is possible to use even substances having a very high boiling point. On account of the fact that the instant of ignition can be set exactly an optimal efficiency for the seed substance is gained which substance is present in a very high distribution.

What I claim is:

1. A rocket for influencing the weather, comprising a shell having a head portion, an explosive charge and a substance to be atomized disposed in said head portion, a thermocouple having one junction thereof soldered and connected to the exterior of said rocket shell and the other end constituting a second soldered junction, a heat insulation means surrounding second soldered junction for maintaining the latter at a constant temperature, a switch means adjustable to a desired thermoelectric voltage and an electrical ignition means for said explosive charge being connected to said thermocouple means, and said switching means for actuating said ignition means and actuating ignition of said explosive charge.

2. The rocket as set forth in claim 1, wherein said electrical ignition means comprises a heated filament and an ignition pellet is surrounded by a core of thermite, and said substance to be atomized surrounds said thermite core.

3. The rocket, as set forth in claim 1 wherein said electrical ignition means is operated at a temperature between -30° and -40°C .
